COIN CHUTE

William C. Shinn, Chicago, Ill., assignor to Chicago Lock Company, Chicago, Ill., a corporation of Illinois

Application November 16, 1934, Serial No. 753,269

11 Claims. (Cl. 194—98)

The present invention relates generally to coin chutes. More particularly the invention relates to that type of coin chute which is designed for use with a coin operated, cabinet encased vending or game machine and comprises: (1) a vertically extending face plate which is adapted to fit against and be secured to the outer face of one of the vertical walls of the cabinet of the machine and embodies a horizontal slot across the central portion thereof; (2) a horizontally extending guide which extends through the slot in the face plate and on both sides of the plate and has the front portion of its side margins bent upwardly and inwardly to form guide flanges; (3) an elongated horizontally extending slide which is mounted slidably on the top face of the guide between the flanges, embodies at its outer end an aperture for a coin of fixed denomination and is adapted when a full inward stroke is imparted thereto, to move the coin inwardly behind the face plate for discharge purposes and to operate the operating mechanism of the vending or game machine; and (4) a spring pressed dog which is mounted on the inner end of the guide and serves when the slide is pushed inwardly without a coin in the coin aperture to prevent a full inward stroke of the slide and actuation of the operating mechanism of the machine.

One object of the invention is to provide a coin chute of this type in which the rear end of the guide underlies and supports a plate which has an upwardly and rearwardly inclined track for receiving coins from the slide during successive inward strokes of the slide and for permitting the played coins to be observed through a glass covered hole or opening in the cabinet of the vending or game machine with which the chute is used.

Another object of the invention is to provide a coin chute of the last mentioned character in which the guide has at the rear end thereof a spring pressed dog which serves during an in-stroke of the slide to raise the rear end of the coin in the coin aperture in the slide and directs it onto the front or receiving end of the track of the plate.

Another object of the invention is to provide a coin chute of the type and character under consideration which includes novel means in the form of a slidable slide controlled finger for advancing a previously played coin on the track when the slide is shifted inwardly in order that an observer of the track may note when the machine has been played without placement of a coin in the coin aperture in the slide.

Another object of the invention is to provide a coin chute of the type and character hereinbefore described, in which sliding movement of the slide with respect to the guide is limited by means of a stop piece which fits in a longitudinal slot in the slide and is held in place against the guide by means of the plate with the coin observing track.

A still further object of the invention is to provide a coin chute of the slide and guide type which is simpler and more efficient than and is generally an improvement upon previously designed chutes of the same general character.

Other objects of the invention and the various advantages and characteristics of the present coin chute will be apparent from a consideration of the following detailed description.

The invention consists in the several novel features which are hereinafter set forth and are more particularly defined by claims at the conclusion hereof.

In the drawings which accompanying and form a part of this specification or disclosure and in which like numerals of reference denote corresponding parts throughout the several views:

Figure 1 is a perspective of a coin chute embodying the invention, the slide of the chute being shown in its retracted position, that is in position to receive a coin in the coin aperture thereof;

Figure 2 is a bottom view of the chute;

Figure 3 is a side view showing the manner in which the chute is applied to the cabinet of a vending or game machine;

Figure 4 is a perspective of the plate which is mounted on the rear end of the guide of the chute and has the upwardly and rearwardly inclined track for receiving played coins from the slide;

Figure 5 is a perspective of the guide;

Figure 6 is a perspective of the face plate;

Figure 7 is a perspective of the stop which serves to limit sliding movement of the slide with respect to the guide;

Figure 8 is a perspective of the slidable, slide controlled finger for advancing a previously played coin on the track during the next in-stroke of the slide;

Figure 9 is a perspective of the slide;

Figure 10 is a vertical longitudinal section of the chute showing the slide in its unretracted position with a coin in the aperture thereof;

Figure 11 is a similar sectional view showing the slide after it has been pushed inwardly and the coin has passed onto the front or receiving

end of the track on the plate above the rear end of the guide;

Figure 12 is a horizontal section taken on the line 12—12 of Figure 11 and showing in detail the construction and arrangement of the plate with the coin observing track; and

Figure 13 is a vertical transverse section taken on the line 13—13 of Figure 10.

The coin chute which forms the subject matter 10 of the invention is shown in the drawings in connection with the cabinet of a game machine M and comprises a substantially rectangular face plate 14, a guide 15, and a slide 16. The machine M is merely representative of the type of machine with which the present coin chute may be 15 employed. As shown in the drawings, the cabinet of the machine embodies a front wall m, an inclined playing board m', and a glass cover m².

The face plate 14 is adapted to fit against the 20 outer face of the front wall m of the cabinet of the machine and embodies in the central portion thereof a horizontally extending slot 17. In addition to the slot the face plate embodies a plurality of holes 18 for screws or like attaching 25 instrumentalities.

The guide 15 extends horizontally and is 30 preferably stamped from sheet metal. It is elongated and projects through the slot 17 in the central portion of the face plate 14 so that it 35 extends on either side of the plate. The outer or front portions of the side margins of the guide are bent upwardly and inwardly to form guide flanges 19. The inner ends of these flanges fit within and terminate adjacent to socket portions 20 at the ends of the slot 17 in the face plate 14. Directly in front of the face plate the guide is provided with a finger opening 21. This opening is circular and is adapted as hereinafter described to be used in connection with the removal of a coin from the slide 16. The rear end of the guide 15 is flat and as shown in Figures 2 40 and 3 of the drawings extends through a rectangular opening m³ in the front wall m of the cabinet of the machine M. A sheet metal bracket 45 22 serves to secure the guide fixedly to the face plate 14 and forms a part of the guide. This bracket overlies and is spaced from the portion of the guide that is directly behind the face plate and embodies depending legs 23 at the sides thereof. These legs as shown in Figure 5 extend 50 through holes 24 in the side margins of the guide 15 and are beaded over at the lower ends thereof so that the bracket is permanently secured to the guide. The front end of the bracket is bent upwardly to form a vertically extending leg 25. This leg fits within a recess 26 in the rear portion or side of the face plate 14 and is permanently and fixedly secured to the face plate by means of rivets 27. The slide 16 is preferably 55 formed of sheet metal and fits slidably on the top face of the guide 15. The side edges of the slide fit in the guide flanges 19 so that the slide is confined to longitudinal sliding movement to and from the face plate 14. The central portion 60 of the slide extends through the slot 17 in the face plate 14 and fits between the bracket 22 and the subjacent portion of the guide 15. The extreme outer or front end of the slide is shaped and bent upwardly to form a finger piece 28 whereby the slide may be grasped manually and 65 slid back and forth in connection with the operation or manipulation of the machine M. Directly behind the finger piece 28 the slide 16 is provided with a circular aperture 29 for a coin of fixed 70 denomination. This aperture is located so that

when the slide is pulled outwardly to its outermost position it overlies and is concentrically arranged with respect to the finger opening 21 in the front end of the guide 15. It is slightly larger than the finger opening so that when a coin of the proper denomination is inserted therein the coin will not drop through the opening 21. When a coin is in the coin aperture 29 and the slide is shifted inwardly, the coin is carried over the guide 15 and is discharged as hereinafter described. The inner or rear end of the slide is adapted to actuate the operating mechanism for the machine after discharge of the coin and as the slide reaches the end of its full inward stroke.

A rectangular plate 30 with a coin track 31 serves as the coin discharging medium for the chute. This plate is preferably in the form of a die casting. It overlies the rear or inner end of the guide 15 and has legs 32 at the corners thereof. These legs, as shown in the drawings, rest on the guide and serve to space the plate above the guide. In addition they engage slidably the side edges of the slide 16 and hold the rear end of the slide against transverse or lateral displacement. Screws 32^a extend through the rear end of the guide and into the legs 32 and operate to secure the plate and guide together in fixed relation. The track 31 is formed in the top face of the plate 30, as shown particularly in Figure 4 of the drawings. It is inclined upwardly and rearwardly and is adapted to receive a coin in the coin aperture 29 of the slide 16 as the slide is shifted inwardly for machine actuating purposes. The front or receiving end of the track leads down to the top face of the slide and the rear or discharge end of the track is curved to one side of the plate 30. The track is adapted, as shown in Figure 14, to hold two coins and is disposed beneath an opening m⁴ 40 in the playing board m' of the machine so that the coins thereon may be observed by looking downwardly over the top of the machine. By virtue of the fact that the track is visible from the outside of the cabinet of the machine through the opening m⁴ it may readily be determined whether the machine has been operated by spurious coins. When there are two coins on the track 31 and the slide 16 is shifted inwardly with a coin in the coin aperture 29, the coins 50 in the track are advanced when the coin in the coin aperture 29 reaches the track 31. During advancement of the coins in the track, the coin in the rear or discharge portion of the track is moved laterally as the result of the shape of the track and is discharged from the plate into a coin receptacle (not shown) in the cabinet of the machine M.

When the slide 16 is shifted inwardly with a coin in the coin aperture 29, the coin approaching the track 31 is tilted upwardly by a dog 34 so that its rear end is properly positioned for entry onto the front or receiving end of the track. This dog is pivotally mounted on a horizontal rod 35 so that it is free to swing vertically. 65 The rod 35 is disposed beneath the portion of the guide that is directly behind the face plate 14 and is supported at its ends by means of oppositely facing ears 36 which are formed integrally with and depend from the guide. The dog 34 70 is urged upwardly through a slot 34^a in the guide by means of a wire spring 37 which is carried by the rod 35. When a coin in the coin aperture 29 of the slide is shifted over the dog 34, the dog as the result of the action of the wire 75

spring 37 presses or forces the rear end of the coin upwardly so that it is aligned with the front or receiving end of the track 31. During further inward stroke of the slide after upward tilting 5 of the coin by the dog 34, the coin is moved onto the track and is forced rearwardly due to the abutting effect of the portion of the slide which forms the front portion of the coin aperture 29. When the slide reaches the end of its inward 10 stroke, the coin is fully disposed on the receiving end of the track as shown in Figure 11. When the slide is retracted the coin remains on the front or receiving end of the track and the coin aperture 29 after passing the face plate 14 15 is in readiness to receive another coin. A leaf spring 38 serves yieldingly to hold the coins on the track 31. This spring is anchored on a stud 38^a at one corner of the plate 30 and has a pair 20 of oppositely extending arms 39 and 40. The arm 39 overlies the front or receiving end of the track and serves yieldingly to hold a coin thereon and the arm 40 overlies the discharge end of the track and prevents a coin thereon from sliding back down the track.

25 Sliding movement of the slide 16 with respect to the guide 15 is limited by means of a stop 42. This stop is in the form of a longitudinally extending bar which is disposed between the plate 30 and the guide and fits in a longitudinal slot 30 43 in the slide. The stop is held against displacement by means of a pair of legs 44 and 45. The leg 44 is located at the front end of the stop and fits in an aperture 46 in the guide. When the slide is shifted inwardly the portion of 35 the slide which defines the front or outer end of the coin aperture 49 strikes against the leg 44 and thus precludes further inward movement of the slide. The leg 45 is located at the rear end of the stop. It fits in an aperture 47 in the rear 40 end of the guide and engages the portion of the slide that defines the rear end of the slot 43 to limit outward movement of the slide. The stop is held in place with the legs thereof in the apertures 46 and 47 by the plate 30 which abuts 45 against its top portion. The leg 44 as shown in Figure 7 has an inclined face 44^a on the upper front corner thereof. This face is so positioned with respect to the front end of the track 31 that it serves to tilt upwardly the rear end of a coin 50 in the aperture 29 as the coin is slid rearwardly. Said inclined face 44^a constitutes positive means for directing or camming the coin from the aperture 29 onto the receiving end of the coin 55 observing track and supplements the action of the dog 34. The slot 43 is centrally disposed with respect to the slide and leads to and communicates with the rear portion of the coin aperture 29. The dog 34 is aligned with the slot 43 with the result that when the slide is retracted it 60 moves upwardly through the slot into the position shown in Figure 10. In this position the dog prevents forward movement of a coin in the front or receiving end of the inclined track 31. Upward swinging of the dog 34 is limited by means 65 of a tongue 22^a on the rear end of the bracket 22. This tongue is inclined upwardly and rearwardly and is disposed directly opposite the front or receiving end of the track 31. When the slide 70 16 is shifted rearwardly with a coin in the coin aperture 29 the tongue 22^a serves to guide the coin into the track as it is tilted upwardly by the dog 34. In addition to guiding the coin into the track it prevents the coin from being snapped out of the coin aperture 29 in the slide by the 75 dog 34.

In order to prevent a full inward stroke of the slide 16 when there is no coin in the aperture 29, dogs 48 and 49 are provided. These dogs are pivotally mounted on a rod and are urged upwardly in the direction of the slide by means of a wire spring 50 on the rod. The dog 48 is centrally mounted on the rod and is arranged in longitudinal alignment with the coin aperture 29. When a coin is in the coin aperture and the slide is pushed inwardly in order to actuate the operating mechanism of the machine M the dog 48 rides under the coin and against the bottom face of the slide. When the coin chute contains no coin and the slide is pushed inwardly the dog 48 enters the aperture as the latter passes there- 15 over. The dog 49 is located at one end of the rod 35 and is rigidly secured to the dog 48 by a cross piece 51 so that it moves conjointly therewith. The outer or distal end of the dog 49 rides against one margin of the slide 16 and is adapted to enter a notch 53, when the dog 48 enters the coin aperture. The outer end of the dog 49 is so shaped that when it is disposed in the notch 53 the slide is locked or held against further inward movement. As shown in the drawings 25 the dogs 48 and 49 and the cross-piece are formed from a single strip of metal by bending the strip into U-shaped design. Said dogs together with the cross-piece constitute a U-shaped device and exemplify novel and improved means for preventing a full inward stroke of the slide when the latter is moved towards its coin discharging position without a coin in the coin aperture. The spring 50 is of the coil type and is mounted on the rod 35 between the dogs 48 and 49. One end 30 of this spring (see Figs. 2, 10 and 11) extends alongside of the dog 48 and is hooked around the dog so that the spring serves to urge the two dogs upwardly towards the slide 16.

For the purpose of advancing to the rear or discharge end of the track 31, a coin on the front or receiving end of the track whenever the slide is pushed inwardly to its fullest extent and there is no coin in the coin aperture 29 as may occur or happen when the dogs 48 and 49 are 45 inoperative as the result of breakage of the spring 50, or are held against operation by insertion of a shim or thin strip of metal between the bottom face of the slide and the top face of the guide, a finger 54 is provided. This finger is carried 50 by a frame 55 which is slidable longitudinally of the guide. As shown in Figure 8 of the drawings the frame 55 is U-shaped in design or configuration and consists of a cross piece 56 and a pair of side pieces 57. The side pieces fit in channels 55 58 in the side portions of the plate 30 and support the frame so that it is slidable in the manner hereinbefore pointed out. The finger 54 is formed of spring metal and is anchored at one end thereof to the cross piece 56 by way of tongues 60 59. The latter are struck upwardly from the cross piece of the frame and are bent over the top face of the finger so as to form an effective anchor for the finger. The other end of the finger is disposed between the two side pieces 57 of the 65 frame and is adapted when the frame is shifted rearwardly to engage the front edge of a coin on the front or receiving end of the track and to shift the coin rearwardly onto the discharge end of the track. The frame is shifted rearwardly 70 by means of an abutment 60 at one side of the slide 16. This abutment is adapted during inward shift of the slide to engage a downwardly extending tongue 61 on one of the side pieces 57 of the frame 55 and through the medium of the 75

tongue to shift the frame together with the finger 54 rearwardly. During retraction of the slide the frame 55 is shifted back to its normal position by means of an abutment 62. The latter is formed on the rear end of the slide and is adapted during the latter portion of the return or retractile movement of the slide to engage the tongue 61 and shift back the frame 55. The abutments 60 and 62 are preferably formed by cutting an elongated notch 63 in one of the side margins of the slide. The tongue 61 together with the abutments 60 and 62 forms a lost motion connection between the finger carrying frame 55 and the slide whereby the frame is shifted rearwardly during the latter portion of the rearward stroke of the slide and is shifted forwardly into its normal position during the latter part of the return stroke of the slide. In the event that the slide 16 is shifted inwardly to its fullest extent when there is no coin in the aperture 29, a coin on the front or receiving end of the track is shifted to the discharge end of the track as the result of the operation of the finger 54. Upon return of the slide to its normal position there will be no coin on the front or receiving end of the track and it will be apparent from this fact that the machine has been played without placement of a coin in the coin aperture 29 of the slide. The coin operating end of the finger is bent downwards and then upwards as shown in the drawings so that when the slide is shifted rearwardly with a coin in the coin aperture 29, it will ride on the top of the coin after the latter is shifted onto the front or receiving end of the track 31. When the slide 16 and the frame 55 are in their retracted positions the coin engaging end of the finger 54 rests on the top face of the slide.

The slide after being shifted inwardly to effect play of the machine M is retracted to its normal position by means of a tension spring 64. This spring is located under and extends longitudinally of the slide and is anchored at its front end to a screw 65 which is carried by a lug 66 on the inner face of the face plate 14. The other or rear end of the spring is attached to a cotter pin 67 on the rear end of the slide. In order to insure a full stroke of the slide after the coin in the aperture 29 is slid into the track 31, a pawl 68 is provided. This pawl is pivotally mounted on a stud 69 at the rear end of the guide 15 and coacts with a plurality of teeth 70 on one of the side margins of the slide. The pawl is urged into contact with the teeth by means of a spring 71 which extends between and is attached to the pawl and a lug 72 on the guide. The pawl is arranged so when the slide is shifted to a point wherein the coin starts to enter the track 31 it coacts with the teeth to prevent retraction of the slide. A cut-out 73 in the slide receives the pawl at the end of the inward stroke of the slide and upon retraction of the slide swings the pawl into a position wherein it rides over the teeth 70. A second cut-out 74 is formed in the slide and receives the pawl at the end of the retractile stroke of the slide and operates during the inward stroke of the slide to swing the pawl into a position wherein it coacts with the teeth 56 to prevent retraction of the slide until after completion of a full inward stroke of the slide.

The operation of the chute is as follows: When it is desired to play the machine M a coin of proper denomination is inserted into the aperture 29 in the front end of the slide 16. Thereafter, a full inward stroke is imparted to the slide. Dur-

ing inward movement of the slide the coin rides on the top face of the guide 15 until it encounters the dog 34 and the inclined face 44^a on the front leg 44 of the stop 42. At this point the coin is tilted upwardly by said dog and face into a position wherein the rear end thereof is aligned with the front or receiving end of the track 31. As the slide continues to move rearwardly the coin slides upwards and rearwards on the track until it is fully disposed in the track and is free with respect to the slide. When the slide after retraction thereof is next operated to effect play of the machine M the coin in the aperture slides into the track 31 and forces rearwardly onto the rear or discharge end of the track the previously played coin. By virtue of the fact that the track is visible through the opening m¹ in the playing board of the cabinet of the machine it is possible to ascertain whether a slug or spurious coin has been used to play the machine. It is also possible because of the operation of the tongue 54 to determine whether the machine has been played without placement of a coin in the coin aperture 29 in the slide.

The herein described coin chute consists of but a small number of parts and hence may be manufactured at a low and reasonable cost. It is extremely efficient in operation and includes simple and novel means for exposing for inspection purposes the two last played coins.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a coin chute of the character described, the combination of an elongated horizontally extending guide, a plate disposed over the rear end of the guide and having an inclined, coin observing track in the top face thereof, an elongated horizontally extending slide provided at its front end with a coin aperture and mounted on the guide to slide rearwardly between the guide and the plate from a coin receiving position to a position wherein the coin aperture therein passes under the plate and then to slide back again, and means for directing a coin in the aperture upwards onto the track during rearward shift of the slide with respect to the guide.

2. In a coin chute of the character described, the combination of an elongated, horizontally extending guide, a rectangular plate disposed over the rear end of the guide and provided with legs at the corners thereof for supporting it from and in spaced relation with respect to the guide and also provided with an inclined coin observing track leading upwardly and rearwardly from the guide, an elongated horizontally extending slide provided at its front with a coin receiving aperture and mounted on the top face of the guide to slide rearwardly between the legs of the plate from a coin receiving position to a position wherein the coin aperture therein passes under the plate and then to slide back again, and means for directing a coin in the aperture upwards onto the track during rearward shift of the slide with respect to the guide.

3. In a coin chute of the character described, the combination of an elongated, horizontally extending guide, a plate carried by and spaced above the rear end of the guide and provided with an arcuate upwardly and rearwardly inclined track

for holding coins for display purposes, an elongated, horizontally extending slide provided at its front end with a coin aperture and mounted on the top face of the guide to slide rearwardly under the plate from a coin receiving position to a position wherein the coin aperture therein passes under the plate and then to slide back again, means operative in response to successive rearward strokes of the slide with respect to the guide to direct coins upwards onto the track, and a leaf spring anchored to the plate and having oppositely extending arms overlying the track and serving yieldingly to hold coins on the track.

4. In a coin chute of the character described, the combination of an elongated horizontally extending guide, a plate carried by and spaced above the rear end of the guide and having in the top face thereof a track for receiving and displaying coins, an elongated slide provided at its front end with a coin aperture and mounted on the guide to slide rearwardly from a coin receiving position to a position wherein the coin aperture therein passes the plate and then to slide back again, and a spring pressed dog for directing a coin in the aperture upwards onto the track during rearward shift of the slide with respect to the guide.

5. In a coin chute of the character described, the combination of an elongated horizontally extending guide, a plate disposed above and supported by the rear end of the guide and having an inclined track in the top face thereof for receiving and displaying coins, an elongated horizontally extending slide provided at its front end with a coin aperture and mounted on the top face of the guide to slide rearwardly from a coin receiving position to a position where the coin aperture therein passes under the plate and then to slide back again, and means for directing a coin in the aperture onto the track during rearward shift of the slide with respect to the guide comprising a dog pivotally supported on the under side of the guide for vertical swinging movement and extending through a slot in said guide, and a spring applied to the dog for urging the same upwardly through said slot and in the direction of the slide.

6. In a coin chute of the character described, the combination of an elongated horizontally extending guide, a plate disposed above and supported by the rear end of the guide and having a track in the top face thereof for receiving and displaying coins, an elongated horizontally extending slide provided at its front end with a coin aperture and mounted on the guide to slide rearwardly from a coin receiving position to a position wherein the coin aperture therein passes under the plate and then to slide back again, and a stationary member carried by the guide for camming a coin in the aperture upwards onto the track during rearward shift of the slide with respect to the guide.

7. In a coin chute of the character described, the combination of an elongated guide, a plate mounted on the rear end of the guide and provided with a track for receiving and displaying coins, an elongated slide provided with a coin aperture in its front end and a longitudinal slot leading rearwardly from the aperture and mounted on the guide to slide rearwardly from a coin receiving position to a position where the coin aperture therein passes the plate and then to slide back again, and a member carried by the

guide so that it fits in the aforesaid slot in the slide and provided with means for camming a coin in the aperture onto the track during rearward shift of the slide with respect to the guide.

8. In a coin chute of the character described, the combination of an elongated horizontally extending guide, a plate positioned over and in spaced relation with respect to the rear end of the guide and provided with an upwardly and rearwardly inclined track for receiving and displaying coins, an elongated, horizontally extending slide provided with a coin aperture in its front end and a central longitudinally extending slot leading rearwardly from said aperture and mounted on the top face of the guide to slide rearwardly between the guide and the plate from a coin receiving position to a position wherein the coin aperture therein passes under the plate and then to slide back again, and a stop in the slot and between the plate and guide operative to limit in and out shift of the slide and having means for camming a coin in the aperture onto the track during rearward shift of the slide with respect to the guide.

9. In a coin chute of the character described, the combination of an elongated guide, a plate mounted on the rear end of the guide and provided with a visible track, an elongated slide provided at its front end with a coin aperture and mounted on the guide to slide rearwardly from a coin receiving position to a position wherein the coin aperture therein passes the plate and then to slide back again, means for directing a coin in the aperture onto the track during rearward shift of the slide with respect to the guide, and means controlled by the slide and operative in response to rearward shift of the latter to advance along the track a coin in the receiving end of the track.

10. In a coin chute of the character described, the combination of an elongated guide, a plate mounted on the rear end of the guide and provided with a visible track, an elongated slide provided at its front end with a coin aperture and mounted on the guide to slide rearwardly from a coin receiving position to a position wherein the coin aperture therein passes the plate and then to slide back again, means for directing a coin in the aperture onto the track during rearward shift of the slide with respect to the guide, and means for advancing coins along the track comprising a movable finger controlled by the slide.

11. In a coin chute of the character described, the combination of an elongated guide, a plate carried by and spaced above the rear end of the guide and provided with a visible track, an elongated slide provided at its front end with a coin aperture and mounted on the guide to slide rearwardly from a coin receiving position to a position wherein the coin aperture therein passes the plate and then to slide back again, means for directing a coin in the aperture onto the track during rearward shift of the slide with respect to the guide, and means for advancing coins along the track comprising a slidably mounted spring finger carried by the plate, and a lost motion connection between the finger and the slide whereby said finger is shifted rearwardly for coin advancing purposes during the latter portion of the rearward stroke of the slide.
